UNITED STATES PATENT OFFICE.

HARLY S. JOHNSON, OF ERWIN, TENNESSEE.

SAFETY DEVICE FOR LOCOMOTIVE TRUCKS.

Application filed March 3, 1925. Serial No. 12,960.

To all whom it may concern:

Be it known that I, HARLY S. JOHNSON, a citizen of the United States, residing at Erwin, in the county of Unicoi and State of Tennessee, have invented certain new and useful Improvements in Safety Devices for Locomotive Trucks, of which the following is a specification, reference being had to the accompanying drawings.

10 This invention relates to safety devices for locomotive trucks and more particularly to a device for indicating derailment of the truck.

An important object of the invention is 15 to provide a device of this character including a signal and means for operating the signal from the air line of the engine so that a test may be made of the signal at any time without disturbing the setting of the 20 automatic feature operating the signal upon derailment of the truck.

A still further object of the invention is 25 to provide a device of this character in which the operating mechanism completes its stroke when the valve controlling the signal has been fully opened and movement of this operating mechanism is positively checked, strain upon the valve and air line being thereby avoided.

30 A still further object of the invention is to provide a device of this character which is very readily attached to both the engine and truck, which is simple in its construction and operation and which may be very 35 cheaply produced.

These and other objects I attain by the construction shown in the accompanying drawings, wherein for the purpose of illustration is shown a preferred embodiment of 40 my invention and wherein:

Figure 1 is a side elevation showing a safety device constructed in accordance with my invention applied to an engine; and

45 Figure 2 is a combined perspective of the various sections of the safety device showing the construction thereof.

Referring now more particularly to the drawings, the numeral 10 indicates a frame member of the locomotive and 11 a frame member of the front truck 12 of the locomotive. A pipe leading from the train line or main reservoir is indicated at 13, this pipe having a cut-off valve 14 arranged therein and having at its terminal a signal 15 to be 50 operated by passage of air through the sig-

nal. This signal is to be arranged in the cab of a locomotive (not herein shown) and may be of any suitable character.

In accordance with my invention, I provide a bracket 16 including a flange 17 adapted to seat upon the frame member 10 and to be secured thereto by bolts 18 or the like. The bracket 16 which extends vertically includes a pair of spaced plates 19 and 20 connected at one end by a wall 12. Through the plates is directed a stop pivot 22 which may consist of a bolt as shown. A bent lever 23 is provided. This lever has formed therein at one end thereof an opening 24 intermediate its ends and at the bend thereof is a slot 25; at its opposite end, is found an opening 26 and intermediate the slot 25 and opening 26 a further opening 27. Between the slot 25 and opening 24, the lever rests upon the upper end of the wall 12, as at 28, and has a shoulder or lug 29 abutting this wall. The slot 25 receives the stop pivot 22 and permits a limited movement of the lever upon this stop pivot.

Secured to the bracket 16 by one of the securing elements 18 thereof is a small bracket 30 having an opening 31 in which is engaged one end of a coil spring 32, the opposite end of which is engaged in the opening 27 of the lever 23 and places strain upon this lever so that normally the lever is positioned so that the upper end of the wall of the slot engages the stop pivot. To the frame element 11 of the truck 12 a coupler 33 is secured, this coupler having a head 34 extending transversely of the frame member and of the engine and formed with a longitudinally extending slot 35. Attached to the lever 23 by means of a bolt 36 extending through the opening 24 is a bracket 37 having a horizontally directed flange 38 through which is directed the stem 39 of an eye bolt, the eye 40 of which is vertically elongated and engaged through the slot 35 of the head 34. By a securing element directed through the opening 26 a swivel 41 is attached to the lever 23 and provides a means for attaching one end of a chain or other suitable flexible element indicated at 42 to the lever. The opposite end of this flexible element is engaged in an opening 43 formed in the handle 44 of the valve 14.

In the operation of the device during normal positioning of the truck and operation of the engine, no movement of the valve 110

handle 44 results, the chain 42 and connections 33, 39 being properly proportioned for this purpose. The connection 34, 35 of the head 34 and eye bolt 40 permits the usual 5 swinging movement of the truck and also permits a slight vertical movement thereof without any tendency to operation of the valve. If anything, there is a tendency during normal operation for the chain 42 to 10 slacken so that absolutely no strain is placed upon the valve handle. This flexible connection will permit operation of the valve handle at any time to make the necessary tests to determine whether the safety signal 15 is operative. These tests of railway safety devices at stated periods are usually required either by laws of the States or of the railway company. When the truck 12 leaves the rails, however, the entire weight of the 20 truck is brought to bear against the short end of the lever by the connection 33, 39, with the result that the long end of the lever is elevated until the stop pivot engages the lower end wall of the 25 slot and checks this movement. This stop pivot is, as disclosed, of heavier material than that employed in the construction of the eye 40 and head 34 and accordingly any increase in strain, instead of moving 30 the lever, will tend to deform or destroy either the eye or the head without transmitting this strain to the valve handle in such manner as to place undue strain upon the pipe connections and cause a break of the 35 train line pipe which would forcibly apply the brakes and possibly increase the damage caused by the derailment of the truck. The opening of the valve 14 by the raising of the long end of the lever 23 will, of course, 40 operate the signal and enable the engineer to bring his train to a gradual stop and very probably without any further damage than that caused by the engagement of the truck with the ties of the road bed.

45 It will be obvious that the structure hereinbefore set forth is capable of a considerable range of change and modification without materially departing from the spirit of my invention and I accordingly do not limit 50 myself to such specific structure except as hereinafter claimed.

I claim:

1. In a safety device for indicating derailment of locomotive trucks and the like, a 55 lever pivoted intermediate its ends upon the main frame of the locomotive, a connection between one end of the lever and the locomotive truck permitting limited transverse and vertical movement of the truck without imparting such movements to the lever, comprising a link connected to the lever and depending from the truck and provided upon its lower end with a vertically elongated eye 60 and an arm secured to the truck and provided upon its upper end with a transversely

extending head having a longitudinally extending slot in which the eye is engaged, a connection between the opposite end of the lever and a control element, a signal operated from the control element and means for limiting movement of the lever in a direction to operate the control element. 70

2. In a signalling device for indicating derailment of locomotive trucks or the like, a bracket mounted upon the frame of the locomotive, a lever pivoted on said bracket, a member directed through the bracket and engaging the lever to limit the pivotal movement thereof, a signal element movable through a certain distance, a signal rendered operative by the element at one limit of its movement, means normally yieldably holding the lever in one position, a connection between the operating element and the lever shifting the operating element to the signal operating position when the lever is moved from its normal position, said limiting member checking movement of the lever when the operating member arrives at its signal operating position, and a connection 80 between the opposite end of the lever and the truck of the locomotive. 85

3. In a signalling device for indicating derailment of locomotive trucks or the like, a bracket mounted upon the frame of the locomotive and including walls arranged at right angles, a lever pivoted on one of said walls and swinging adjacent the other of said walls, a member directed through the other wall and engaging the lever to limit the pivotal movement thereof, a signal element movable through a certain distance, a signal rendered operative by the element at one limit of its movement, means normally yieldably holding the lever in one position, a connection between the operating element and the lever shifting the operating element to the signal operating position when the lever is moved from its normal position, said member directed through said other wall of said bracket limiting movement of the lever when the operating member arrives at its signal operating position and a connection between the opposite end of the lever and the truck of the locomotive. 100 105

4. In a signalling device for indicating derailment of locomotive trucks or the like, a bracket mounted upon the frame of the locomotive and including walls arranged at right angles, a lever pivoted on one of said walls and swinging adjacent the other of said walls, a member directed through the other wall and engaging the lever to limit the pivotal movement thereof, a signal element movable through a certain distance, a signal rendered operative by the element at one limit of its movement, means normally yieldably holding the lever in one position, a connection between the operating element and the lever shifting the operating ele- 110 115 120 125 130

ment to the signal operating position when the lever is moved from its normal position, said member directed through said other wall of said bracket limiting movement of the lever when the operating member arrives at its signal operating position and a connection between the opposite end of the lever and the truck of the locomotive, the connection between the lever and the signal operating member being flexible to thereby permit manual manipulation of the operating member to test the signal.

5. In a signalling device for indicating derailment of locomotive trucks or the like, a bracket mounted upon the frame of the locomotive and including walls arranged at right angles, a lever pivoted on one of said walls and swinging adjacent the other of said walls, a member directed through the other wall and engaging the lever to limit the pivotal movement thereof, a signal element movable through a certain distance, a signal rendered operative by the element at

one limit of its movement, means normally yieldably holding the lever in one position, 25 a connection between the operating element and the lever shifting the operating element to the signal operating position when the lever is moved from its normal position, said member directed through said other wall of 30 said bracket limiting movement of the lever when the operating member arrives at its signal operating position, a connection between the opposite end of the lever and the truck of the locomotive, comprising a link 35 connected to the lever and depending toward the truck and provided upon its lower end with a vertically elongated eye and an arm secured to the truck and provided upon its upper end with a transversely extending 40 head having a longitudinally extending slot in which the eye is engaged.

In testimony whereof I hereunto affix my signature.

HARLY S. JOHNSON.
